UNITED STATES PATENT OFFICE.

JAMES HUGHES, OF MOUNT VERNON, IOWA.

ELEVATED-RAILWAY SWITCH.

SPECIFICATION forming part of Letters Patent No. 775,300, dated November 22, 1904.

Application filed November 28, 1902. Serial No. 133,154. (No model.)

To all whom it may concern:

Be it known that I, JAMES HUGHES, a citizen of the United States, residing at Mount Vernon, in the county of Linn, in the State of Iowa, have invented a new and useful Elevated-Railway Switch, of which the following is a specification.

This invention relates to elevated railways, and has for its object to produce a simple and convenient method of switching cars from a track at one level to another at a lower or higher level.

The nature of the invention will fully appear in the description and claims following, reference being had to the accompanying drawings, in which--

Figure 1 is a side elevation illustrating my improved switching apparatus as applied to two tracks at different levels. Fig. 2 is a plan view of the same. Fig. 3 is an end view showing the track shifting or switching mechanism.

In the drawings, A denotes the arched sub-structure of an elevated railway. Above this, supported by posts B, are two tracks C and D, respectively, the latter above the former high enough to allow cars to pass under it. To switch cars from one of these tracks to the other is the subject-matter of this invention, and the apparatus for this purpose will now be described.

A portion of the lower track E is inclined, as shown, until the top of the grade is about half-way to the level of the upper track. Corresponding to this inclination of the lower track the upper track has a section F inclined in the opposite direction, with the free ends of its rails beveled to rest on top of the lower rails, as shown in Fig. 1. The other end adjoins the level upper track, and the inclined section of track is adapted to swing laterally, as shown in Fig. 2. The switch-track is supported by gooseneck-hangers G, having roller H to run on top of girders I, supported by the posts B'.

The mechanism for shifting the switch-track sidewise is shown in Fig. 3. J is a winch,

to which is connected a cable K, making a number of turns about it. The ends of the cable are attached to opposite sides of the switch-track, respectively. The winch is actuated by a train of gearing L, mounted between the posts B' and B² and operated through the medium of a crank M.

The operation of the device is so simple as to require little description. Swung to one side, as shown in Fig. 2, the lower line is open for the passage of cars along it. When, however, it is desired to transfer a car moving to the right to the upper track, the switch-track is swung over parallel with the lower track, and the car may then pass up the grade to said upper track.

Having thus described my invention, what I claim as new, and desire to secure by Letters Patent, is--

1. The combination of elevated - railway tracks at different levels, the lower track having an ascending inclined portion, an oppositely-inclined section of track leading to the upper track, with one end free to swing side-wise, supporting posts and girders for said tracks, hangers with antifriction - rollers to support the swinging track on cross-girders, and means substantially as described to swing said track back and forth.

2. The combination of elevated tracks at different levels, the lower track having an upwardly-inclined section, a downwardly-inclined switching-section connecting with the upper track, posts, girders, and hangers with antifriction-rolls to support said switch-track, a winch provided with suitable gearing and crank, and a cable connecting said winch at opposite ends with opposite sides thereof, substantially as described.

In testimony whereof I have signed my name to this specification in the presence of two subscribing witnesses.

JAMES HUGHES.
